OR D 15,008

No. 15,008

May 20, 1884

UNITED STATES PATENT OFFICE.

WILLIAM H. JACKSON AND JOHN H. HANKINSON, OF NEW YORK, N. Y.

DESIGN FOR A FIRE-PLACE HEATER.

SPECIFICATION forming part of Design No. 15,008, dated May 20, 1884.

Application filed February 11, 1884. Term of patent 7 years.

To all whom it may concern:

Be it known that we, WILLIAM H. JACKSON and JOHN H. HANKINSON, citizens of the United States, residing at New York, in the county of New York and State of New York, have invented and produced a new and original Design for Fronts of Fire-Place Heaters, of which the following is a specification, reference being had to the accompanying drawing, forming part thereof.

The drawing shows a perspective view of our newly-designed front for fire-place heaters.

The several dissimilar figures in relief, as arranged upon the front projecting part of a fire-place heater and upon its easing, constitute the distinguishing features of this design.

That portion of the design above and at the sides of the heater (denoted by letter A) represents a frame or easing with raised moldings 20 as an outer margin, beaded indented molding as an inner border, with overlapping disks or scales B on the intermediate raised surface, as shown in the drawing. Within this border a series of diverging ribs and grooves, C, radiate from the upper corners, terminating at the circular boundary-line of that part of the design on the projecting heater.

Across the front, and extending back at the sides, there are projecting ledges D D' D'', dividing the design into four sections, 1 2 3 4. Sections 1 and 2 are ornamented with open

scroll-work on panels P. Section 3 has the figure representing the salamander upon its two panels P'; and section 4 represents a cupola in the center, with double arched reticulated roof, and at each side of the cupola (above ledge D'') is the figure of an inverted basket, 5.

The figures upon the doors of the cupola consist of intersecting curved lines or ribs, the prominent feature of which resembles an inverted heart.

At the sides of the projecting heater the sections 1 2 3 are ornamented with open rectangular gratings standing out in high relief. 45

One of the basket-ornaments 5 and one of the doors of section 3 are omitted from the drawing.

Having described our invention, we claim—

The design for fire-place heaters, consisting 50 of the figures (referred to and denoted by letters) on sections 1 2 3 4, and the ornamentation on frame or easing A, herein shown and described.

Witness our hands this 21st day of December, 55 A. D. 1883.

WILLIAM H. JACKSON.
